UNITED STATES PATENT OFFICE.

JAMES G. MACLAREN, OF MAMARONECK, NEW YORK.

CARRIER-DISTRIBUTER.

1,367,162.

Specification of Letters Patent.

Patented Feb. 1, 1921.

Application filed January 22, 1915, Serial No. 3,677. Renewed August 20, 1917. Serial No. 187,254.

To all whom it may concern:

Be it known that I, JAMES G. MACLAREN, a resident of Mamaroneck, county of Westchester, and State of New York, have invented certain new and useful Improvements in Carrier-Distributors, of which the following is a specification.

This invention relates to carrier distributors for carrier systems, and is intended to receive carriers from a common transmission means and separate or distribute them according to classes. The invention is more particularly concerned with a distributor especially adapted for use in connection with a pneumatic despatch tube apparatus, but its usefulness is by no means limited to pneumatic systems. Where the distributor is used in connection with a pneumatic despatch system carriers despatched through a common tube are sorted according to classes and distributed to the desired points.

The uses of the distributor are many, and it may be adapted to a wide variety of situations and distribute the carriers for delivery in any direction or at any distance. The carriers may be delivered by the distributor into suitable separate hoppers, or may be re-despatched in other pneumatic tube lines, or may be deposited on traveling belts or other means for further transmission.

One of the principal uses of the device is the separation of carriers containing cash from those containing charge account slips, so that upon arrival at the central station the carriers containing cash pass to cash operators, while those containing charge slips pass to charge operators, thus avoiding danger of confusion and mixing of carriers of different classes.

My invention will be best understood by reference to the following description when taken in connection with the accompanying drawings of one specific embodiment thereof, while its scope will be more particularly pointed out in the appended claims.

In the drawings:

Figure 1 is an elevation, partly in vertical section, of a carrier distributor embodying my invention showing the parts in the position which they normally occupy;

Fig. 2 is an elevation, partly in vertical section, of the carrier distributor viewed from the opposite side to that shown in Fig. 1, and showing the parts in one of the positions which they occupy when distributing carriers;

Fig. 3 is a detail sectional view on line 3—3 of Fig. 1;

Fig. 4 is a detail elevation of one form of carrier head or buffer; and

Fig. 5 is a detail elevation of a similar head or buffer, but provided with a projection.

Referring to the drawings and to the embodiment of my invention which I have selected for illustration, I have there shown a portion of a carrier apparatus having carrier transmission means which may be of any usual or desired type, but is herein a pneumatic despatch tube R. The carriers for the transmission of cash slips or other things may be of any usual or desired type, but I have herein shown a common form of carrier S. These carriers are of two classes, differing in form, size or other characteristic whereby they are adapted for coöperation with suitable selecting means. In the present example the two classes of carriers are provided one with a head G having a projecting plug G⁶, and the other with a head or buffer having no such projection. (See Figs. 4 and 5.)

The carriers are transmitted through the common transmission tube R regardless of the classes to which they belong, and are delivered one at a time into a suitable receiver A. This receiver may be of any suitable form, and may have associated therewith any suitable means for causing the sorting or distribution of the carriers according to the class to which they belong. In the present example, as a means for selecting carriers according to classes, I have provided two abutments G' and H' of different heights, best shown in Fig. 3, mounted to slide vertically in a suitable guide F. The abutment G' is adapted for coöperation with the projecting plug G⁶ of a carrier of one class, while the abutment H' is adapted for coöperation with the head or buffer H of a carrier of another class.

The carrier entering the receiver impinges upon one or the other of these abutments according to the class to which it belongs, and thereupon such abutment acts through suitable means to cause the carrier to emerge from the receiver at one side or another of the path of travel of the carrier as it entered the receiver. In the present instance the abutments G' and H' are a form of rods mounted to slide in a vertical direction and adapted to be depressed by the impact of the car-

riers. Any suitable means, such for example as the springs G^2 and H^2 , may be employed normally to hold the abutments G' and H' in their uppermost positions and to restore them to such positions after having been depressed by the impact of carriers.

The abutments may actuate any suitable form of motor to cause the sorting or distribution of the carriers according to classes.

- 10 This motor may take a variety of forms, but in the present example it is of the pneumatic type and comprises the piston B mounted to work in a cylinder B^3 . Opposite ends of this cylinder are herein connected by pipes C , C' and D , D' to a common supply pipe E , and the volume of fluid which passes through these pipes may be regulated by suitable means, such for example as needle valves C^2 and D^2 , thereby to regulate the 20 speed of travel of the piston B . A supply pipe E may be connected to any suitable source of supply (not shown), which may supply air pressure to or exhaust air from the supply pipe.

- 25 Normally there will be an equality of the pressures on opposite sides of the piston B . This normally existing balance of pressures may be unbalanced by any suitable means under the control of the abutments G' and H' . In the present example, for this purpose I have provided vent pipes C^3 and D^3 communicating with the pipes C and D respectively on opposite sides of the piston B , and leading to chambers F' and F^2 respectively controlled by venting valves H^3 and G^3 .

Assuming that the supply pipe E is connected to an exhaust so that pressure below that of the atmosphere normally exists on 40 opposite sides of the piston B , when a carrier impinges upon and depresses one of the abutments G' and H' the corresponding venting valve operated by such abutment is opened, thereby admitting atmospheric air into one end of the cylinder faster than air is exhausted therefrom through the restricted opening provided by the needle valve controlling that side of the cylinder. It follows that with this unbalancing of the 50 previously balanced pressures on opposite sides of the piston, the latter will move toward one end or the other of its cylinder according to which of the abutments was struck by the carrier.

- 55 The movement of the piston may be utilized in any suitable manner to cause the displacement of the carrier in one direction or another according to the class to which it belongs. To this end the receiver A is movable from its normal position in alinement with the transmission tube R to one side or the other of the path of travel of the carrier as it enters the receiver, and the latter may be suitably connected to the piston as by 60 means of a piston-rod B' and link B^2 .

The receiver A may be supported for such movement by any other suitable means, but herein is mounted on tracks J , J . The receiver may be, and preferably is, provided with two sets of rollers A' , A^2 and A^3 70 adapted to travel on the tracks J , J . As means for causing the restoration of the receiver to its normal position after having been displaced therefrom through the action of the piston, the force of gravity may 75 be utilized by making the two tracks J , J oppositely inclined so that the receiver constantly tends to gravitate to its normal position in alinement with the despatch tube as shown in Fig. 1. With this arrangement 80 it is preferable to make the middle rollers A^2 larger in diameter than the others to correspond with the inclination of the tracks J , J , and to maintain the receiver always 85 in a vertical position.

It must be evident that when the receiver is displaced toward one side or the other of its normal position, some means must be provided to take care of any succeeding carrier arriving at the terminal of the transmission 90 tube R , and to this end the upper portion of the receiver is laterally extended in opposite directions, shown in Figs. 1 and 2, to form two abutments. Under such circumstances the succeeding carrier impinges upon one or 95 the other of these abutments and is arrested until the receiver is restored to its normal position, whereupon the carrier drops into the receiver.

When one venting valve or the other is 100 opened, as hereinbefore described, to cause the displacement of the carrier to one side or the other according to the class to which it belongs, the valve should remain open a sufficient length of time to insure the displacement of the carrier to the desired point, and then close. To this end I have herein provided two latches G^5 and H^5 , normally resting against the lateral surfaces of collars G^4 and H^4 secured to the rods G' and 110 H' respectively. (See Fig. 1.) These latches are normally pressed inwardly against their respective collars by a spring M encircling a shaft N , on which the latches are pivoted.

When one of the abutments, as for example the abutment G' (see Fig. 2) is depressed by the impact of a carrier, the collar G^4 passes below its latch G^5 and is thus locked in its depressed position against the 120 upward tendency of the spring G^2 . The other abutment is locked in a similar manner by the other latch.

As a means for unlocking the abutments at the proper times in the operation of the 125 distributor, I have herein provided triggers K and L to actuate the latches G^5 and H^5 respectively, these triggers being arranged in the path of the carriers in such a way as to be displaced from the positions which they 130

normally occupy, and thereby to act through one venting valve or the other to cause the restoration of the receiver A to its normal position. These triggers may be otherwise suitably arranged, but in the present example I have shown two hoppers O and P to receive the carriers of two classes from the receiver A, and these hoppers are laterally apertured to receive the triggers K and L.

It will be evident that as a carrier enters one receiver or the other, it will displace the corresponding trigger in a lateral direction, and thus act through the corresponding latch to release the previously opened venting valve and allow the same to close under the influence of its spring.

While I have herein shown and described one form or embodiment of my invention for illustrative purposes, and have disclosed and described in detail the construction and arrangements incidental to one specific application thereof, it is to be understood that the invention is limited neither to the mere details or relative arrangement of parts, nor to its specific embodiment herein shown, but that extensive deviations from the illustrative form or embodiment of the invention may be made without departing from the principles thereof.

Having thus described one embodiment of my invention, what I claim and desire by Letters Patent to secure is:—

1. In a carrier distributor for pneumatic despatch tube apparatus, a transit tube for the transmission of carriers, a receiver for the carriers upon their discharge from the transit tube, a motor for operating said receiver, means actuated by the carrier upon its entering into said receiver for starting said motor in operation to move said receiver to deliver said carrier, and means for returning the receiver to its normal position after the carrier has been discharged from the receiver.

2. In a carrier distributor for pneumatic despatch tube apparatus, a transit tube for the transmission of carriers, a receiver for the carriers upon their discharge from the transit tube, a motor for operating said receiver, means actuated by differently formed carriers for starting said motor in operation to move said receiver to deliver the carriers, and means for returning the receiver to its normal receiving position after the discharge of the carrier from said distributor.

3. In a carrier distributor for pneumatic despatch tube apparatus, a transit tube for the transmission of carriers, a receiver for the carriers upon their discharge from the transit tube, a motor for operating said receiver, means actuated by differently formed carriers for starting said motor in operation to move said receiver to deliver the carriers, and means actuated by the discharging carrier for returning the receiver to its normal

receiving position after the discharge of the carrier from said distributor.

4. In a carrier distributor for a pneumatic despatch tube apparatus, a transit tube for the transmission of carriers, a receiver for the carriers upon their discharge from the transit tube, a motor for operating said receiver and adapted to be actuated by differently formed carriers to move the receiver in different directions for the discharge of the carrier, means for normally holding the receiver in position to receive the carriers from the transit tube, and means adapted to be actuated by one form of carrier to release and move the receiver in one direction to deliver a carrier and another form of carrier to release and move the receiver in another direction to deliver a carrier.

5. In a carrier distributor for a pneumatic despatch tube apparatus, a transit tube for the transmission of carriers, a receiver for the carriers upon their discharge from the transit tube, a motor for operating said receiver and adapted to be actuated by differently formed carriers to move the receiver in different directions for the discharge of the carrier, means for normally holding the receiver in position to receive the carriers from the transit tube, means adapted to be actuated by one form of carrier to release and move the receiver in one direction to deliver a carrier and another form of carrier to release and move the receiver in another direction to deliver a carrier, and means controlled by the exit of a carrier for returning the receiver into alignment with the transit tube to receive the next carrier.

6. In a carrier distributor for a pneumatic despatch tube apparatus a transit tube for the transmission of carriers, a receiver for the carriers upon their discharge from the transit tube, pneumatically controlled mechanism for operating said receiver and adapted to be actuated by differently formed carriers to move the receiver in different directions for the discharge of the carrier, means for normally holding the receiver in position to receive the carriers from the transit tube, and means adapted to be actuated by one form of carrier to release and move the receiver in one direction to deliver a carrier and another form of carrier to release and move the receiver in another direction to deliver a carrier.

7. In a carrier distributor for a pneumatic despatch tube apparatus, a transit tube for the transmission of carriers, a receiver for the carriers upon their discharge from the transit tube, pneumatically controlled mechanism for operating said receiver and adapted to be actuated by differently formed carriers to move the receiver in different directions for the discharge of the carrier, means for normally holding the receiver in position to receive the carriers from the transit tube,

- means adapted to be actuated by one form of carrier to release and move the receiver in one direction to deliver a carrier and another form of carrier to release and move 5 the receiver in another direction to deliver a carrier, and means controlled by the exit of a carrier for returning the receiver into alinement with the transit tube to receive the next carrier.
- 10 8. In a carrier distributor for pneumatic despatch tube apparatus, a transit tube for the transmission of carriers of different classes, a receiver for the carriers upon their discharge from the transit tube, a motor for 15 moving said carriers out of register with the transit tube, and means selectively actuated by the carriers upon their entering into said receiver for starting said motor to deliver the carriers in different directions according to 20 the classes to which they belong.
9. In a carrier distributor, the combination of a receiver for the carriers, a motor for operating said receiver, means actuated by a carrier upon its entry into said receiver for starting said motor into operation to move said receiver to deliver said carrier, and means for causing the return of said receiver into its normal position after said carrier has been discharged from 30 said receiver.
10. In a carrier distributor, the combination of a receiver for the carriers, a motor for operating said receiver, means actuated by differently formed carriers for starting said motor into operation to move said receiver in different directions to deliver said carriers, and means for causing the return of said receiver to its normal receiving position after the discharge of the carrier from 35 the distributor.
11. In a carrier distributor, the combination of a receiver for the carriers, a motor for operating said receiver, means actuated by differently formed carriers for starting said motor into operation to move said receiver in different directions to deliver the carriers, and means actuated by the discharging carrier for causing the return of said receiver to its normal receiving position after the discharge of the carrier from 45 the distributor.
12. In a carrier distributor, the combination of a receiver for the carriers, a motor for operating said receiver and adapted to be actuated by differently formed carriers to move said receiver in different directions for the discharge of the carrier, means for normally holding the receiver in position to receive the carriers, and means adapted to be actuated by one form of carrier to move said receiver in one direction to deliver a carrier and by another form of carrier to move said receiver in another direction to deliver a carrier.
- 65 13. In a carrier distributor, the combina-
- tion of a receiver for the carriers, a motor for operating said receiver and adapted to be actuated by differently formed carriers to move said receiver in different directions for the discharge of the carriers, means for normally holding said receiver in position to receive the carriers, means adapted to be actuated by one form of carrier to move the receiver in one direction to deliver a carrier and by another form of carrier to move 70 said receiver in another direction to deliver a carrier, and means controlled by the emerging carrier for causing the return of said receiver into position to receive the next carrier.
14. In a carrier distributor, the combination of a receiver for the carriers, pneumatically controlled mechanism for operating said receiver and adapted to be actuated by differently formed carriers to move said receiver in different directions for the discharge of the carrier, means for normally holding the receiver in position to receive the carriers, and means adapted to be actuated by one form of carrier to move said receiver in one direction to deliver a carrier and by another form of carrier to move said receiver in another direction to deliver a carrier.
15. In a carrier distributor, the combination of a receiver for the carriers, pneumatically controlled mechanism for operating said receiver and adapted to be actuated by differently formed carriers to move said receiver in different directions for the discharge of the carrier, means for normally holding the receiver in position to receive the carriers, means adapted to be actuated by one form of carrier to move said receiver in one direction and by another form of carrier to move said receiver in another direction to deliver a carrier, and means controlled by the emerging carrier for causing the return of said receiver into position to receive the next carrier.
16. In a carrier apparatus, the combination of means for transmitting carriers toward a given destination, and instrumentalities for separating said carriers according to classes upon their arrival at such destination, said instrumentalities including a motor and means operated by impact of said carriers to energize said motor and cause the same to convey the carriers bodily in one direction or another according to their classes.
17. In a carrier apparatus, the combination of means for transmitting carriers toward their destination, and instrumentalities for distributing said carriers according to classes upon their arrival at such destination, said instrumentalities including a cylinder and a piston to convey said carriers bodily in one direction or another according to their classes.

18. In a carrier apparatus, the combination of means for transmitting carriers toward their destination, and instrumentalities for distributing said carriers according to classes upon their arrival at such destination, said instrumentalities including fluid-controlled means to convey said carriers bodily in one direction or another according to their classes.
19. In a carrier apparatus, the combination of means for transmitting carriers toward their destination, and instrumentalities for distributing said carriers according to classes upon their arrival at such destination, said instrumentalities including a cylinder and a piston working therein and set into motion by impact of a carrier, to shift the latter laterally in one direction or another.
20. In a carrier apparatus, the combination of means for transmitting carriers toward their destination, and instrumentalities for distributing said carriers according to classes upon their arrival at such destination, said instrumentalities including motor means energized by said carriers to propel said carriers and to cause the same to move in one direction or another according to their classes.
21. In a carrier apparatus, the combination of means for transmitting carriers toward their destination, and instrumentalities for distributing said carriers according to classes upon their arrival at such destination, said instrumentalities including motor means energized by impact of said carriers to propel said carriers and to cause the same to move in one direction or another according to their classes.
22. In a carrier apparatus, the combination of means for transmitting carriers toward their destination, and instrumentalities for distributing said carriers according to classes upon their arrival at such destination, said instrumentalities including motor means energized by engagement with the forward ends of said carriers to propel said carriers and to cause the same to move in one direction or another according to their classes.
23. In a carrier distributor, the combination of a receiver for the carriers, a motor for operating said receiver, means actuated by a carrier received by said receiver for causing said motor to move said receiver from a normal mid-position in generally opposite directions therefrom, and means for causing the restoration of said receiver to said mid-position.
24. In a carrier apparatus, the combination of means for causing carriers to travel lengthwise in a path in one direction, and carrier-arresting and assorting instrumentalities including means in said path to arrest such travel, and motor means ener-
- gized by the last-mentioned means to set said carriers into motion again and to cause them to be assorted by lateral movement in different directions according to their classes.
25. In a carrier apparatus, the combination of means for causing carriers to travel lengthwise in a path in one direction, and carrier-arresting and assorting instrumentalities including means in said path and mounted to move in such direction to arrest such travel, and motor means energized by the last-mentioned means to set said carriers into motion again and to cause them to be assorted by lateral movement in different directions according to their classes.
26. In a carrier apparatus, the combination of means for causing carriers to travel lengthwise in a path in one direction, and carrier-arresting and assorting instrumentalities including yieldingly mounted means in said path, to arrest such travel, and motor means energized by the last-mentioned means to set said carriers into motion again and to cause them to be assorted by lateral movement in different directions according to their classes.
27. In a carrier apparatus, the combination of a carrier receiver, means to deliver carriers of different classes to said receiver, means constantly tending to maintain said receiver in a carrier-receiving position, and carrier-actuated motor means acting in opposition to the last-mentioned means, to move said receiver to any one of a plurality of carrier-delivering positions depending upon the class to which the actuating carrier belongs.
28. In a carrier apparatus, the combination of a carrier receiver, means to deliver carriers of different classes to said receiver, means to utilize gravity normally to maintain said receiver in a carrier-receiving position, and carrier-actuated means acting in opposition to the effect of gravity to move said receiver to any one of a plurality of carrier-delivering positions depending upon the class to which the actuating carrier belongs.
29. In a carrier apparatus, the combination of means for transmitting carriers of different classes to a common receiving point, a carrier impact-receiving member at said point, and carrier impact-energized motor means to distribute said carriers in different directions according to the different classes to which they belong.
30. In a carrier apparatus, the combination of a transit tube through which carriers of different classes are delivered at a common receiving point, and instrumentalities selectively to deliver carriers from said receiving point according to the classes to which they belong, said instrumentalities

ties including a pressure fluid operated member normally subject to balanced opposed pressures, and carrier-actuated means to unbalance said pressures.

5 31. In a carrier apparatus, the combination of a transit tube through which carriers of different classes are delivered at a common receiving point, and instrumentalities selectively to deliver carriers from said 10 receiving point according to the classes to which they belong, said instrumentalities including a pressure fluid operated member normally subject to balanced opposed pressures, and two carrier-actuated, 15 pressure-unbalancing valves to cause said member to move in opposite directions, respectively.

32. In a carrier apparatus, the combination of a transit tube through which carriers of different classes are delivered at a common receiving point, and instrumentalities selectively to deliver carriers from said receiving point according to the classes to which they belong, said instrumentalities 20 including a pressure fluid operated member normally subject to balanced opposed pressures, and two carrier-actuated, pressure unbalancing valves to render opposite sides, respectively, of said member one at 25 a time, subject to pressure of the atmosphere.

33. In a carrier apparatus, the combination of a transit tube through which carriers of different classes are delivered at a common receiving point, and instrumentalities selectively to deliver carriers from said receiving point according to the classes to which they belong, said instrumentalities including a pressure fluid operated member 35 normally subject to balanced opposed pressures, carrier-actuated means to unbalance said pressures, and means operated by movement of said member in one direction to deliver carriers of one class at one point and 40 operated by movement of said piston in the opposite direction to deliver carriers of another class at another point.

34. In a carrier apparatus, the combination of a transit tube through which carriers of different classes are delivered at a common receiving point, and instrumentalities selectively to deliver carriers from said receiving point according to the classes to which they belong, said instrumentalities including a pressure fluid operated member 50 normally subject to opposed balanced pressures, carrier-actuated means to cause an unbalancing of said pressures, and carrier-actuated means to cause a restoration of the 55 balance of said pressures.

35. In a carrier apparatus, the combination of a transit tube through which carriers of different classes are delivered at a common receiving point, and instrumentalities

selectively to deliver carriers from said receiving point according to the classes to which they belong, said instrumentalities including a pressure fluid operated member normally subject to opposed balanced pressures, carrier-actuated valves to cause an unbalancing of said pressures, means to lock said valves in unbalanced pressure positions, and carrier-actuated means to unlock said valves and allow the same to resume their 65 normal positions. 70 75

36. In a carrier apparatus, the combination of a transit tube through which carriers of different classes are delivered at a common receiving point, and instrumentalities selectively to deliver carriers from said receiving point according to the classes to which they belong, said instrumentalities including a pressure fluid operated member normally subject to opposed balanced pressures, different from that of the atmosphere, carrier-actuated valves to cause an unbalancing of said pressures by subjecting one side or the other of said member to pressure of the atmosphere, means to hold one valve or the other in its unbalanced-pressure 85 position, and carrier-actuated means to release such valve and allow the same to resume its normal position. 90 95

37. In a carrier distributor for pneumatic despatch tube apparatus, a transit tube for the transmission of carriers of different classes, a receiver for the carriers upon their discharge from the transit tube, said receiver having a carrier-receiving chamber open to the atmosphere, a receiver-actuating motor, 100 and means selectively actuated by the carriers upon their entrance into said receiver to cause said motor to actuate said receiver to deliver the carriers to different destinations according to the classes to which they belong. 105

38. In a carrier distributor for pneumatic despatch tube apparatus, a transit tube for the transmission of carriers of different classes, a receiver for the carriers upon their discharge from the transit tube, said receiver having a carrier-receiving chamber having provision to deliver carriers independently of carrier-propelling air current in said transit tube, a receiver-actuating motor, and means selectively actuated by the carriers upon their entrance into said receiver to cause said motor to actuate said receiver to deliver the carriers to different destinations according to the classes to which they belong. 110 115

39. In a carrier apparatus, the combination of means for transmitting carriers toward a given destination, and instrumentalities for separating said carriers according to classes upon their arrival at such destination, said instrumentalities being independent of said means and including a motor and means operated by impact of said carriers to energize said motor and cause the 120 125

same, independently of said means, to direct the carriers toward either of two destinations according to their classes.

40. In a carrier apparatus, the combination of means including a transmission tube for transmitting carriers toward a given destination, and instrumentalities for separating said carriers according to classes upon their arrival at such destination, said instrumentalities including a motor and means outwardly beyond the outlet end of said tube and operated by engagement with said carriers to arrest the carriers and to energize said motor and cause the same to urge 10 the carriers in one direction or another according to their classes.

41. In a carrier apparatus, the combination of means including a transmission tube for transmitting carriers toward a given 20 destination, and instrumentalities for separating said carriers according to classes upon their arrival at such destination, said instrumentalities including a motor and means operated by endwise engagement with

the advancing ends of said carriers to energize said motor and cause the same to move said carriers bodily in one direction or another according to their classes and in directions different from their direction of travel in emerging from said tube. 25

42. In a carrier apparatus, the combination of means for transmitting carriers toward their destination, and instrumentalities for distributing said carriers according to classes upon their arrival at such destination, said instrumentalities including motor means energized by said carriers to change the direction of travel of said carriers and to cause them to move in one direction or another according to their classes. 30

In testimony whereof, I have signed my name to this specification in the presence of two subscribing witnesses, this 15th of January, A. D. 1915.

JAMES G. MACLAREN.

A. F. AUGENBACHER,
ELSIE MACLAREN.

Correction in Letters Patent No. 1,367,162.

It is hereby certified that in Letters Patent No. 1,367,162, granted February 1, 1921, upon the application of James G. Maclaren, of Mamaroneck, New York, for an improvement in "Carrier-Distributors," an error appears in the printed specification requiring correction as follows: Page 5, line 84, claim 26, for the word "carries" read *carriers*; and that the said Letters Patent should be read with this correction therein that the same may conform to the record of the case in the Patent Office.

Signed and sealed this 15th day of March, A. D., 1921.

[SEAL.]

M. H. COULSTON,

Commissioner of Patents.
